[57] CLAIM

The ornamental design for an inflatable slide, as shown and described.

DESCRIPTION

FIG. 1 is a perspective view of an inflatable slide showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side view thereof; the right side view being a mirror image thereof;

FIG. 7 is a front view thereof with landing bumper shown separated for clarity of illustration. The slide body is shown in partial broken lines for ease of illustration; and,

FIG. 8 is a left side view thereof; similar to FIG. 6, but the step shown in extended position for clarity of illustration.

FIG.1.

FIG.2.

FIG.3.

FIG.4.

FIG.5.

FIG.6.

FIG.7.

FIG.8.
